(57) CLAIM

The ornamental design for a toilet paper holder cabinet, as shown and described.

DESCRIPTION

FIG. 1 is a front perspective view of the toilet paper holder cabinet showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a second front perspective view thereof, shown in an alternative position of use.

The broken lines shown in the drawings represent portions of the toilet paper holder cabinet that form no part of the claimed design.
